LOAD TRANSFER DEVICE

Alan E. Brickman, Rostravore Township, Westmoreland County, Pa., and George A. Gleason, Worcester, Mass., assignors to The American Steel and Wire Company of New Jersey, a corporation of New Jersey

Continuation of application Serial No. 161,685, August 30, 1937. This application September 28, 1938, Serial No. 232,201

13 Claims.

(Cl. 94—18)

The present invention relates to a load transfer device for transverse joints in concrete roadways, walks and the like.

An object of this invention is to provide a load transfer device across a joint in a concrete roadway or pavement having complementary units, of identical construction, for movement relative to each other upon the expansion and contraction of the roadway or pavement.

10 Other objects and advantages will become apparent as the description proceeds, and reference is made to the accompanying drawing, in which:

Figure 1 is a side elevation of the present invention in position at a joint in a concrete roadway or pavement;

Figure 2 is a section on the line II—II of Figure 1;

Figure 3 is a section on the line III—III of Figure 1; and

20 Fig. 4 is a view similar to Fig. 2 showing the free ends of each housing bent outwardly to form resilient wings.

Referring more particularly to the drawing, the load transfer device of the present invention includes two complementary units, designated generally at A and B, said units being identical in construction.

Each unit forming one-half of the transload device comprises two nubbed half-oval plates 2 and 3 maintained in spaced relation to each other by dowel plates 4 with the flat faces of said plates 2 and 3 facing each other, said dowel plates being resistance welded (or otherwise secured in any conventional manner) to the nubs 1 on said half-ovals 2 and 3. The half-ovals have their ends 6 bent laterally from the normal horizontal plane of said ovals so as to form, with the nubs 1, a good bond in the concrete sections.

The dowel plates 4 are each provided with a 40 dowel portion 4' provided with a rack 5 which is cut or stamped therein. Cover plates or housings 8, of spring-like metal are welded, in any conventional manner to said dowel plates and are provided with a pawl 9 adapted to engage said 45 racks 5 and cooperate therewith to provide means for initially holding the complementary units, forming the joint assembly in proper position upon the roadbed until the poured concrete has set. After the load transfer device has become 50 embedded in the concrete, the cooperative action of the pawl and rack may become inoperative by shear through subsequent relative movement of the concrete.

The free ends of each cover plate or housing 8 55 are bent outwardly on an angle, as shown in

Figure 4, to the main body portion to form resilient wings 10 for properly aligning the dowel device in relation to the filler and, if necessary, to provide a yieldable condition to obtain a more rigid assembly. One of the wings 10 of each cover plate or housing is bent laterally to form a flange 12 extending backwardly in a plane parallel to the main body portion of said cover plates or housings, and thus affords a means for disengaging the pawl and rack to make initial adjustments, if desired. Opened end dowel receiving pockets 14 of a depth not less than the length of said dowel portion 4' and within which the dowel portions 4' of said dowel plates 4 are adapted to slide relative to each other are formed by the dowel plates 4, housings 8 and half-oval plates 2 and 3. The horizontal edges of the dowel portion 4' of each dowel plate 4 are in sliding contact with the horizontal edges 14' of said dowel receiving pockets 14 and thereby provide means for transferring the loads from one concrete slab to the adjacent slab so that the surface upon which vehicles travel is maintained in substantial alignment across the transverse joint and will permit expansion and contraction of the concrete slabs. The dowel plates are secured, in any conventional manner, to one wall of said housings in such a manner that, upon projection into the pocket of the adjacent unit, there is provided a space within which is placed an elastic filler 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 assembly appears as shown in Figure 1. Under the construction hereinabove described, there is provided a device which will assemble to any form of transverse joint.

5 The bent ends 6 of the half-ovals and the nubs formed thereon cooperate to form a good bond in the concrete, while the rounded side of the straight length of the half-ovals forms increased dimension for better stress distribution, non-
10 cleavage forming edges, and permits favorable flow of the wet concrete mix around the joint unit. The straight flat face of the half-ovals forms load transfer bearings for the vertical dowels while the latter, being vertical and operating transversely, provides the greatest strength for the amount of material used and permits two like units to be used in the assembly.

15 The present application is a continuation of an application filed by us August 30, 1937, Serial Number 161,685.

20 While we have shown and described a specific embodiment of the invention, it will be understood that we do not wish to be limited exactly thereto since various modifications may be made thereto without departing from the scope of the invention, as defined by the following claims.

We claim:

1. A load transfer device for roadway joints comprising vertically positioned complementary units aligned in spaced relation to each other transversely of the roadway joint and provided with dowel receiving pockets, a dowel extending outwardly beyond the end of the pocket of each unit and arranged in reverse slidable contact 25 with each other and slidably fitting into the pockets of the respective units and means on said units for anchoring said units within the concrete.

2. A load transfer device for roadway joints comprising vertically positioned complementary structural units spaced in aligned relation to each other at the roadway joint, dowels carried by each unit and arranged in reverse slidable contact with each other, dowel receiving pockets 45 formed on each structural unit for slidably receiving the dowel of the complementary unit and means carried by each unit for anchoring said units within the concrete.

3. A load transfer device for roadway joints comprising vertically positioned complementary structural units spaced in aligned relation to each other at the roadway joint, dowels carried by each unit and arranged in reverse slidable contact with each other, dowel receiving pockets 55 formed on each structural unit for slidably receiving the dowel of the complementary unit and means for initially restraining displacement of the dowel of one unit from the dowel receiving pocket of the other unit.

4. A load transfer device for roadway joints comprising complementary structural units spaced in aligned relation to each other at the roadway joint, vertically positioned dowel plates carried by each unit and arranged in reverse slidable 65 contact with each other, a dowel receiving pocket of a depth substantially corresponding to the vertical dimension of said dowel formed on each structural unit for slidably receiving the dowel of the complementary unit and an elastic filler member positioned within the space between the end of said dowel and said pocket.

5. A load transfer device for roadway joints comprising complementary structural units spaced in aligned relation to each other at the roadway joint, vertically positioned dowel plates carried by 70

each unit and arranged in reverse slidable contact with each other, a dowel receiving pocket of a depth substantially corresponding to the vertical dimension of said dowel formed on each structural unit for slidably receiving the dowel of the complementary unit. 5

6. A load transmission joint for concrete roadways and pavements comprising vertically positioned complementary units, said units including spaced-plates, dowel-plates welded to said spaced-plates, cover-plates for said dowel-plates, each of said dowel-plates secured to and extending beyond the free ends of each of said cover-plates and slidable in a plane perpendicular to the roadway within a pocket formed in the other 10 complementary unit, and means for initially holding the complementary units together during the pouring of the concrete.

7. In a load transmission joint for concrete roadways and pavements, complementary units 20 positioned vertically between adjacent concrete slabs, said complementary units including plates spaced in superimposed relation to each other, a dowel bar secured to each spaced-plate and arranged in reverse slidable contact with one 25 another in a plane perpendicular to the roadway, a cover-plate secured to the spaced-plate of each complementary unit and so constructed and arranged as to provide a dowel receiving pocket for the reception of the dowel bar of the adjoining 30 complementary unit, said cover-plate completely enclosing one end of said dowel and rigidly secured thereto, the other end of said dowel extending beyond the end of said cover-plate and into slidable contact with the dowel 35 receiving pocket of the adjoining complementary unit and means on said cover-plate and dowels for initially holding said complementary units together during the pouring of the concrete and permitting expansion and contraction thereof. 40

8. A load transfer device for the adjacent ends of concrete slabs, comprising at least two elongated force transmitting members embedded in the slabs and longitudinally disposed in transverse relation across and substantially at right 45 angles to the joint between the ends of the slabs, said members being disposed on edge in vertical planes in the concrete and one having horizontally projecting flanges engaging and embracing the edges of the other to prevent relative vertical movement therebetween and between the ends of the slabs, while permitting relative longitudinal movements on horizontal lines. 50

9. A load transfer device for the adjacent ends of concrete slabs, comprising a pair of similar, 55 mating plates standing on edge and each having a portion embedded in the concrete adjacent one end of the slab, the embedded portion of each plate comprising horizontal flanges and spaced vertical walls connected thereto, forming a 60 socket and excluding the concrete from the interior thereof, each plate including a longitudinally extending, forwardly projecting end portion disposed transversely across and bridging the space between the slabs and disposed in the 65 socket of the other, between and embraced by the horizontal flanges of the latter, to prevent relative transverse movement of the members in a vertical plane, while permitting relative longitudinal movement on horizontal lines. 70

10. A load transfer device for the adjacent ends of concrete slabs, comprising a pair of similar, mating members longitudinally disposed transversely across the joint between the slabs and each anchored in one slab, each member com- 75

prising a horizontally extending, elongated plate lying in a vertical plane and having laterally projecting, horizontal flanges along one portion, closely embracing and mating with the side edges 5 of the other end of the other member.

11. A load transfer device for the adjacent ends of concrete slabs, comprising a pair of similar, mating members longitudinally disposed transversely across the joint between the slabs, 10 each member comprising a plate lying in a vertical plane, having one portion provided with horizontal flanges embedded in the end of one slab, and a forwardly projecting plate continuation standing on edge in a vertical plane and 15 slidably disposed between and closely embraced by the corresponding horizontal flanges of the other member.

12. A load transfer device for the adjacent ends of concrete slabs, comprising a pair of longitudinally arranged, juxtaposed, elongated plates standing on edge, each of said plates having a portion embedded in the concrete at one end of a slab and a forwardly projecting portion 20 extending across the joint and into the other slab, said embedded portion of each plate hav-

ing a pair of horizontal flanges projecting toward the juxtaposed, forward portion of the other plate and closely embracing the top and bottom edges thereof to prevent relative vertical movement between the plates and between the 5 adjacent slab ends.

13. A load transfer device for the adjacent ends of concrete slabs, comprising a pair of longitudinally arranged, juxtaposed, elongated plates standing on edge, each of said plates having a portion embedded in the concrete at one end of a slab and a forwardly projecting portion 10 extending across the joint and into the other slab, said rear portion having a pair of horizontal flanges projecting toward the juxtaposed, forward portion of the other plate and embracing the edges thereof to prevent relative vertical movement between the plates and between the adjacent slab ends, and a shield plate associated 15 with said flanges and disposed to shield the forward portion of the other plate from contact with the concrete.
